UNITED STATES PATENT OFFICE.

HARRY E. ADAMS, OF TOLEDO, OHIO, ASSIGNOR TO THE MONROE ELECTRICAL MANUFACTURING COMPANY, OF MONROE, MICHIGAN, A CORPORATION OF MICHIGAN.

GROUND-CLAMP.

972,489.

Specification of Letters Patent.

Patented Oct. 11, 1910.

Application filed June 28, 1909. Serial No. 504,768.

To all whom it may concern:

Be it known that I, HARRY E. ADAMS, a citizen of the United States, and a resident of Toledo, in the county of Lucas and State of Ohio, have invented a certain new and useful Ground-Clamp; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to electrical appliances, and has particular reference to clamps of the class adapted for connecting ground-wires to pipes, rods or other similar conducting means projecting into the ground.

20 The object of my invention is the provision of a simple, improved and highly efficient clamp of this class, which is strong and durable in its construction, inexpensive of manufacture, and adapted to have perfect 25 contact with the ground-rod or pipe entirely around the same, thus enhancing its practicability and commercial value.

The invention is fully described in the following specification, and a preferred embodiment thereof illustrated in the accompanying drawings, in which,—

30 Figure 1 is a side view of the clamp secured to a ground-pipe. Fig. 2 is a cross-section on the line $\alpha\alpha$ in Fig. 1. Fig. 3 is 35 a perspective view of the same removed from the ground-pipe, and Fig. 4 is a top plan view of a portion of the clamp.

Referring to the drawings, 1 designates the saddle or bridge member of the clamp, 40 which is substantially U-shape in cross-section and has its legs each provided with an opening 2. A screw 3 is threaded through the loop or body portion of the saddle 1 and carries a wire socket 4, to which a ground-wire 5 is secured in any suitable manner, 45 and also carries a nut 6, which serves both to coöperate with the screw to rigidly clamp the socket 4 to the saddle and as a lock-nut for securing the screw in set position, as 50 shown.

The strap or band 7, which is of flexible electrical conductive material and coöperates with the saddle 1 and screw 3 to clamp and closely embrace the ground-pipe or rod 55 8, has one end attached to the bar or part

9 of the saddle forming the outer wall of one of the openings 2 thereof. A simple and preferred method of attaching the strap to the saddle consists in passing an end of the strap inwardly through one of the openings 60 2 and then wrapping it completely around the bar 9 of the saddle, as shown. In order to provide a more secure anchoring of the strap to the bar 9, such bar is provided on its inner edge with a lug 10, which projects 65 through a registering opening 11 in the strap end, and prevents an unwinding of the strap end from the bar due to longitudinal pull thereon.

Provided preferably in a broadened part 70 of the strap 7 near the end thereof which is attached to the saddle 1 is a slot 12 through which the free end of the strap is passed after making a single convolution around the article to which the saddle is to be 75 clamped. The end of the strap after passing through such slot embraces the portion of the first formed convolution which is opposed to the saddle 1 and is then projected through the two openings 2, 2 of the 80 saddle from the side thereof opposed to the bar 9 and under the inner end of the screw 3. The strap having been drawn by hand as tightly as possible around the ground-pipe or rod 8, the screw 3 is turned inwardly to 85 force the contacting portion of the strap against the registering portion of the inner convolution of the strap which has a firm bearing on the ground-member 8, thus securely clamping such end of the strap 90 against longitudinal movement relative to the saddle. On a continued turning of the screw the saddle is forced outwardly from the ground-member and a consequent tightening of the strap around such member effected thus drawing the same in close contact with the entire circumference of the member.

It is apparent that the strap 7 when engaged to a ground-member 8, describes two 100 complete convolutions around the same, and is in perfect contact with the entire surface of the member encompassed thereby, while the other or outer convolution attaches to the saddle; it is also apparent that this form 105 of clamp is capable of easy and quick application to or removal from a ground pipe or the like.

I wish it understood that my invention is not limited to any specific construction or 110

arrangement of the parts except in so far as such limitations are specified in the claims.

Having thus described my invention what I claim as new and desire to secure by Letters Patent, is,—

- 5 1. In a ground-clamp, the combination with an article to be clamped, of a saddle having openings in the legs thereof, a strap attached at one end to one leg of such saddle 10 thence passing entirely around the article and having an opening through which the free end of the strap extends, thence passes partially around the article-embracing convolution of the strap and projects through 15 the openings in said saddle, and a screw carried by the saddle with its end in contact with the portion of the strap disposed between said openings and operative to co-operate with the saddle and said article to 20 effect a tightening of the strap around the article.
2. In a ground-clamp, the combination with the article to be clamped, of a saddle having bars at opposite sides thereof, one of 25 such bars having a lug projecting therefrom, a strap coiled around the article and having one end wrapped around the bar provided with said lug and having an opening receiving said lug and its other end being 30 extended across both of said bars, means acting on said strap and co-operating with the saddle and said article to effect the tighten-

ing of the strap around the article, and a wire attaching member secured to said saddle.

35

3. A ground clamp, comprising a saddle having an opening in each end portion thereof, a band attached at one end to one end of the saddle and having its other end projected through both end openings of the 40 saddle, and a screw threaded through the saddle intermediate said openings and bearing at its inner end against the free end portion of the band, substantially as described.

4. A ground clamp, comprising a saddle 45 having an opening in each end portion thereof, a band attached at one end to an end of the saddle, thence twice encircling an article to be clamped with its free end projected through both openings of the saddle, 50 and a screw threaded through the saddle intermediate said openings with its inner end bearing against the free end portion of the band and holding it in contact with the other loop of the band, substantially as de- 55 scribed.

In testimony whereof I have hereunto signed my name to this specification in the presence of two subscribing witnesses.

HARRY E. ADAMS.
